UNITED STATES PATENT OFFICE.

ERNST CHRISTENSON, OF STOCKTON, KANSAS, ASSIGNOR OF ONE-FOURTH TO
WILLIAM I. SMITH, OF STOCKTON, KANSAS.

CAR DOOR.

Application filed January 31, 1920. Serial No. 355,321.

To all whom it may concern:

Be it known that I, ERNST CHRISTENSON, a citizen of the United States, residing at Stockton, in the county of Rooks and State of Kansas, have invented certain new and useful Improvements in Car Doors; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to car doors and particularly to means for converting an ordinary box car into a grain car.

Since the sliding side doors of box cars are not adapted to function properly when grain is contained within the box car, it has been the practice to provide supplemental doors, either in sections or in single members to serve as a supplemental closure or dam to prevent the grain from escaping from the car door opening. Various means have been provided for accomplishing the desired result, the most common practice being to drive spikes into the woodwork of the cars to secure the door or door sections in place. A repeated application of this practice materially mars the wood work and requires repairs to restore the car to its original condition.

I have provided means whereby the box car may be utilized as an ordinary freight car in the usual way but when it is necessary to transport grain, a sectional door will be available so that the door opening may be closed in an efficient and expeditious manner without the necessity of driving nails, spikes or other fastening devices into the wood-work, an important feature being that the door is always available when needed.

The device is so constructed that the sections may be normally restored out of the way of the proper functioning of the box car but when necessary, the sections may be lowered into functional position to serve as an obstruction across the door opening in a manner clearly indicated in the drawings, in which—

Fig. I is a perspective view from the inside of the car showing my invention in functional position in the door opening.

Fig. II is a transverse elevational view

of the operating mechanism, the door sections being shown in cross section and moving into functional position.

Fig. III is a cross sectional view of the door sections moving into inoperative position, and

Fig. IV is a cross sectional view through the door, showing the elevator in plan.

Referring now to the drawings by numerals of reference:

1 designates a box car of approved construction having a door opening 2, the sides of which are bound by the vertical posts 3 and 4. The inner faces of the respective posts are provided with continuous elongated grooves 5 and 6, in which are section placing devices, adapted to operate therein. The inner portions 7 and 8 of the respective grooves have their floors 9 inclined inwardly from the top to the bottom, as clearly indicated in Fig. III, the floors 9 being effective in controlling the position of the car door section placers whereby the proper sections will be disposed upon the proper hangers, as will be presently described.

The mechanism for operating the door sections is best shown in Figs. I, II and IV, the driving mechanism being shown as secured to one of the posts, in the present instance post 3. Upon post 3 is mounted a sprocket wheel 10 driven by a crank 11, the teeth of the sprocket meshing with a chain 12, passing around an upper sprocket 13 and a lower sprocket 14, the two sprockets being in line so as to insure that a portion of the chain will at all times travel in a substantially perpendicular path as at 15, Fig. II. The chain traveling in the path as at 15 meshes with a sprocket 16 on a transverse rod or cylinder 17, which extends entirely across the door opening and carries gears 18 and 19 at its respective ends, which mesh with the vertical racks 20 and 21 in slots in the inner sides of the posts 3 and 4 so that as the chain passes over the sprocket 16, the sprocket will be rotated and inasmuch as it is rigid on the cylinder or rod 17, carrying the gears 18 and 19, the gears will be rotated over the racks and thereby cause the cylinder or rod to be raised or lowered, dependent upon the direction of rotation of the crank 11. The cylinder or rod is provided with bracket arms 22 and 23, which are loosely mounted on the member 17 and these bracket

100

105

110

arms support a transverse rod 24, on which

the section placers 25 and 26, which are shown as bifurcated members, are loosely mounted, each of which is provided with an inwardly projecting hook extension 27, adapted to carry a plurality of door sections 28, the door sections being provided with hook engaging notches 29 and 30 whereby the hooks may engage them. Similar support-engaging notches 31 and 32 are provided on each section 28 and these are adapted to engage the supporting brackets 33 and 34, arranged in spaced relation and in rows on the posts 3 and 4, as will be apparent by reference to Figs. II and III.

15 The placers are held in proper position and away from the edges of the posts by the rollers 35 and 36 on the rod 24, and the hooked ends 27 of the placers slide in the inner portions 7 and 8 of the grooves 5 and 6, the ends 37 of the hooks 27 being adapted to slide against the floors 9 of the grooves. For example, if the parts are assembled with all of the sections suspended from the hooked ends of the placers 25 and 26, the operator may turn the crank 11 in a counter-clockwise direction, causing the chain 12 to travel over the sprocket 16 so as to rotate the gears 18 and 19 on the cylinder 17, whereby the elevator, consisting of the cylinder, the rod 24 and its complementary mechanism, will be lowered. As the placers move downwardly in the outside portions of the grooves 5 and 6, the hooked ends of the placers will ride down the grooves at a uniform shallow depth, and the door sections 28 will be held outwardly away from engagement by any of the hooks or supports 33 and 34. When the elevating or positioning mechanism reaches the bottom of the grooves, the hooked ends will move across into the portions 7 and 8 of the endless groove so that the ends will bear against the floors 9. Then the direction of rotation of the handle 11 will be reversed to raise the elevating or placing mechanisms until the first inner section is adjacent to the hooks or brackets 33 and 34. A slight lowering of the placers will permit the hooks 33 and 34 to engage the notches 30 and 31 of the first section 28. While the operator manipulates the crank with one hand, he may with the other swing the placer hooks out of the grooves and away from the door section just placed upon the hooks 33 and 34 and then 55 elevate the remaining door sections to deposit the next succeeding door section upon the next higher set of hooks 33 and 34.

60 The operation just described will continue until the requisite number of door sections are in place. It will be apparent that the above operation can be accomplished and since the floors 9 of the inner portions of the grooves incline outwardly and upwardly, the hooked portion 37 will move into the 65 groove approximately the thickness of the

first section so that the second section 28 may be deposited upon its supporting brackets and this operation may continue for each succeeding section and set of brackets to build up the sectional door to the desired 70 height. Then the hooks or placers are removed from the top section and the elevator may be raised to a position at the top of the door opening, there being a pawl or other fastening means for the sprocket 16, if desired. 75

When it is desired to remove the door sections, the elevating or carrying mechanism is lowered so that the hooks may, on account of their upturned ends, glide over the edge 80 of the projecting portion 28' of the top door section and hook thereunder to place the section on the hook, the hooks are then raised slightly to free the section from the hooks 33 and 34 after which the hooks are lowered to the next section and so on progressively, until all of the sections are on the hooks, whereupon the sections may be elevated to be stored in a space at the top of the door opening until it is desired to use 90 them again.

Attention is called to the fact that the placers 25 and 26 may automatically transfer from one groove portion to the other when the placer reaches either the upper or 95 lower end because the two groove sections are connected together by transverse inclined portions so that a continuous groove is formed, the floors of the transverse portions being inclined upwardly and outwardly. 100 The hangers 25 and 26 are so constructed that they tend to spring to the side or toward the outside groove so that when they reach the top of the groove 8 and engage the incline, they will readily move over into 105 the outer groove.

It will be apparent from the foregoing that the sections may be quickly and accurately put in place and removed by manipulating the handle 11 so that the car may be 110 converted into a grain car or an ordinary box car at the will of the operator.

What I claim and desire to secure by Letters-Patent is:

1. In a device of the class described, door section hangers, a plurality of door sections, door section placers normally supporting said sections, and means for raising and lowering the door section placers into and out of proximity with the respective door section hangers whereby the door sections may be transferred from the hangers to the placers and vice versa. 115

2. In a device of the class described, a plurality of door hangers arranged in vertical rows, a plurality of door sections, means for supporting said door sections, and means for bringing the door section supporting means in proximity to the door hangers whereby the door sections may be trans- 120 125 130

fferred from the door supporting means to the door hangers.

3. In a device of the class described, the combination with a pair of uprights constituting the sides of a door opening, door section hangers on said uprights, a lowering and elevating means, door sections, door section placers on the elevating means and normally supporting the door sections, and means for operating the elevating means whereby the door placers may deposit the door sections upon the hangers.

4. In a device of the class described, spaced vertical rows of door hangers, door sections having means for engaging said hangers, door section placers removably engaging said sections, and means for moving the door section placers vertically toward and away from the door hangers whereby the door placers may be moved into position to transfer the door sections onto the door hangers and vice versa.

5. In a device of the class described, a transverse bar, door section placers carried by said bar, means for raising and lowering said bar, door sections removably engaging said placers, and door hangers in the path of movement of the placers whereby a movement of the placers in one direction will be effective in depositing the sections upon the hangers and a movement of the placers in an opposite direction will remove the sections from the hangers.

6. The combination of a pair of uprights, having grooves of progressively increasing depths, door section placers vertically movable in said grooves and having ends bearing

against the floors of said grooves, door sections carried by said placers, and door section hangers in the path of movement of 40 said door sections.

7. In a device of the class described, an endless chain, a transverse bar vertically movable through the medium of said chain, hooked members carried by said bar, door 45 sections removably engaging said hooked members, and hangers for engaging the door sections when the hooked members move in one direction.

8. In combination, parallel uprights, having endless grooves longitudinally arranged therein, each groove comprising two parallel portions and one portion of each groove being of progressively increasing depth, the other portion of each groove being of shallow uniform depth, hooked members operable in said grooves, each hooked member being transferable from one groove of each pair to the other groove of the pair, door sections carried by the hooked members, and 55 rigid door section-supporting means in spaced relation adjacent to the grooves.

9. In combination, a pair of spaced uprights, a manually operable endless chain carried by one of the uprights, a transverse 65 elevating device guided in the uprights, and moving in response to movement of the chain, hooked placers carried by the elevating device, door sections removably supported by said placers, and door section 70 hangers on the uprights, disposed to receive the door sections from the hooked placers.

In testimony whereof I affix my signature.

ERNST CHRISTENSON.
